UNITED STATES PATENT OFFICE.

HERMAN HEINE, OF BROOKLYN, NEW YORK, ASSIGNOR TO A. KIMBALL COMPANY, OF NEW YORK, N. Y., A CORPORATION OF NEW YORK.

PIN-TICKET MACHINE.

1,339,887.

Specification of Letters Patent. Patented May 11, 1920.

Application filed December 9, 1913. Serial No. 805,632.

To all whom it may concern:

Be it known that I, HERMAN HEINE, a subject of the Czar of Russia, residing at Brooklyn, county of Kings, State of New York, have invented an Improvement in Pin-Ticket Machines, of which the following description, in connection with the accompanying drawing, is a specification, like characters on the drawing representing like parts.

This invention relates to machines for making pin tickets for attaching to merchandise of various kinds and more particularly to an automatic device for making wire pins or staples having doubled wire prongs for such tickets. The invention may be embodied in a machine of the general type of that shown in the patent to Kimball No. 457,782 granted August 18, 1891.

The invention has for an object to provide mechanism for making staples having prongs of doubled wire folded at the points.

Another object is to provide an automatic mechanism for making pin tickets in which the wire will be doubled at the points of the pin so that the pin when in use will not have sharp or jagged points to catch the threads of merchandise or injure the fingers.

In accordance with my present invention I provide a mechanism for making staples having doubled wire prongs and attaching these staples to blanks of cardboard or other material. The staple-forming mechanism includes means for bending the wire to a U-shape and means for folding or doubling the ends of the wire whereby the finished staple will present doubled wire prongs. In the embodiment illustrated the means for bending the wire operates first and the doubling means afterward, the order of operation however is not material.

The nature and objects of the invention will be more fully understood from the following specification and accompanying drawings in which the novel features will be particularly described and then pointed out in the appended claims.

Referring to the drawings in which I have illustrated a selected embodiment of my invention,

Figure 1 is front view of a part of a pin ticket machine constructed in accordance with my invention;

Fig. 2 is a plan view of the same;

Fig. 3 is a sectional view taken on the line 3—3 Fig. 2;

Fig. 4 is a front view of the hammers of a staple forming mechanism, showing also the wire cutting mechanism partly in section;

Fig. 5 is a sectional view taken on the line 5—5 Fig. 4 showing the staple forming mechanism;

Figs. 6, 7 and 8 are sectional views of the staple forming mechanism, the parts being shown in the different positions occupied during the staple forming operation;

Fig. 9 is a perspective view of the staple after it has been carried from staple forming position to the driving position the anvil being shown in dotted lines;

Fig. 10 is a similar view of the staple after it has been partially applied to the card, the card being shown in dotted lines; and

Fig. 11 is a similar view showing the staple applied to the card, the card being shown in dotted lines.

Referring to the drawings in detail, a supporting frame is indicated at 1. On this frame is mounted a bed, 2, which supports the staple-forming and driving mechanism and the wire feeding mechanism, a stand, 3, secured to the bed providing convenient means for the attachment of certain parts. Power is supplied by front and rear cam shafts 4 and 5, which are geared together to rotate in unison as by a shaft 6, and miter gears connecting each cam shaft thereto. These shafts may be driven from any suitable source of power.

Any convenient form of wire-feeding mechanism may be employed, it being essential only that predetermined lengths of wire should be delivered to the staple-forming mechanism. In the form illustrated, a strand of wire 7 is intermittently fed through the hard steel die 8 secured in a bracket 9 fast to the stand, by a feeding mechanism comprising a slide 10, with a lever 11 pivoted thereon and operated by a link 12, controlled by a lever 13 and a cam 14 on the forward cam shaft. The rearward movement of the lever relative to the slide is limited by an adjustable stop 15 in the form of a wedge positioned against a stop pin 16 and held in adjusted position by a set screw. A jaw 17 is carried by the lever and is adapted to clamp the wire 110

against a corresponding jaw on the slide. The movement of the slide depends upon the amount of free movement of the lever relative to the slide and may therefore be 5 adjusted by means of the wedge 15, thus determining the length of wire to be fed. Upon each rotation of the cam the slide is moved forward and back, the wire being automatically gripped between the jaws on 10 the forward movement of the slide and released upon the return movement thus providing an adjustable intermittent feed. A knife 18 is slidably mounted adjacent the die and serves to cut the wire after each 15 feeding movement. The wire is fed through the die on a line above the plane of the bed and upon being cut, is dropped into position to be operated upon.

Wire bending devices receive the lengths 20 of wire and bend them to form staples having double prongs, these devices comprising in the embodiment illustrated a die or former movable to and from operative position, a plunger and folder movable relative to the die and hammers to compress the 25 prongs. It will be obvious, however, that the necessary relative movements of the parts may be obtained in other ways than that illustrated. The former is indicated at 30 19 secured to the lower end of a slide 20 and provided with two parallel flanges 21 and 22 around which the wire is bent to staple form. The slide 20 is vertically movable in a way 23 in the back of the face plate 24. 35 The operation of the former and of the knife are such that both may be conveniently controlled by the same cam. Accordingly the slide is connected at its upper end to a bolt 25 to which bolt the knife 18 40 is also connected as by a clamp. An operating lever 26 pivoted at 27 and controlled by the cam 28 on the rear cam shaft engages this bolt and thereby operates the knife and former. A plunger 29 having a wire receiving 45 groove 30 around its edge is adapted to engage the severed wire at its middle point and draw it through the former between the flanges 21 and 22 thus bending the wire to an approximate U-shaped form as shown 50 in Fig. 6, the end of the wire being brought into engagement with the grooved fingers 31 and 32 of a folder 33. The plunger 29 preferably fits rather closely between the flanges of the former. The folder is adapted 55 to move forwardly folding the ends of the wire against the outer side of the flanges 21 and 22 thus giving the wire the form shown in Fig. 7. The plunger 29 is slidably mounted in the folder 33 which in turn is 60 slidably mounted in the folder guide 34 secured to the bed. The plunger 29 is operated by a lever 35 pivoted at 36 and controlled by the cam 37 on the forward cam shaft. A link 38 connects the lower end of 65 the lever to the plunger. The folder 33 is

operated by a lever 39 pivoted at 40 and controlled by a cam 41 on the forward cam shaft. After the ends of the wire have been folded about the flanges of the former the folder is withdrawn and the former raised 70 by their respective cams. I prefer to provide mechanism to compress the folded ends of the prongs in order that the points may be as small as possible and in order that the parts of each prong may lie close 75 together. In the embodiment illustrated the prongs are compressed against the plunger 29 after the former and folder are withdrawn by hammers 42 and 43 the groove 30 in the plunger being of a depth equal to 80 twice the thickness of the wire to receive the prongs. These hammers are pivoted to the face plate 24 by the screw bolt 44 and are operated by links 45 and 46 connected to the upper ends of the hammers and to a link 47 85 operated by a lever 48 pivoted at 49 and controlled by the cam 50 on the rear cam shaft. The face plate 24 to which the hammers are pivoted, is secured in place on a plate 51 fast on the stand 3, by six screws 52. Retaining mechanism may be provided to temporarily hold the staple on the plunger during the withdrawal of the former and folder and until the hammers have engaged the 90 staple. Such mechanism may conveniently be carried by the hammers and in the embodiment illustrated consists of arms 53 and 54 pivoted to the hammers by screw bolts 55 and 56 respectively and pressed inwardly by springs 57 and 58 secured to the hammers. The screw bolts 55 and 56 preferably extend through holes in the hammers and are screwed into tapped holes in the arms so as to be readily accessible from the front of the machine. The relative movement of 105 each arm is limited by a pin 59 secured in the hammer and projecting into a hole 60 in the arm, the difference between the sizes of the pin and hole being such as to permit the desired movement of the arm relative to the 110 hammer. When the arms are in their outermost position relative to the hammers the faces of the arms are even with the faces of the hammers. These arms are pressed inwardly by their springs and are adapted to 115 engage the pin before the folder is entirely withdrawn so as to hold the pin in position on the plunger as the folder and former are retracted, the respective cams being so timed that the hammers will be moved toward 120 each other sufficiently to permit the arms to engage the pin when the folder is only partially retracted, the hammers engaging the pin after the folder has been entirely retracted and the former raised.

Any desired type of staple driving mechanism may be employed. I have illustrated a mechanism similar to that shown in the previously mentioned patent to Kimball and this mechanism is arranged back of the 130

staple forming mechanism. It is therefore necessary to provide means to transfer the staple from the staple forming position to the driving position. The means illustrated is most clearly shown in Figs. 3 and 8. The staple having been formed on the plunger 29 is held in the groove thereof by the hammers and their pivoted arms directly in front of an opening, 61, in the plate 51 and 24 the hammers forming guides to prevent the ends of the wire catching against the plates at the edges of the opening. The plunger is adapted to move through this opening carrying the staple to position over the anvil 62 of the driving mechanism. A spring-pressed retaining catch 63 pivoted to the stand at 64 engages the loop of the staple and holds it in place as the plunger is withdrawn. The end of the plunger is recessed, as indicated at 65 to permit the catch to engage the loop of the staple. A plunger 66 descends as the plunger 29 is withdrawn and clamps the staple against the anvil, the plunger 66 being operated by a lever 67 pivoted at 68 controlled by a cam 69 on the rear cam shaft. The opening 61 in the plates 5 and 24 are of substantially the size of the outside of the staple and thus assists in holding the staple in proper position for driving.

The blanks usually in the form of a strip of cardboard are fed across the machine between the guides 70 and 71. The feeding mechanism for the blanks as to its specific construction forms no part of my present invention. This mechanism is illustrated as of the same construction as shown in the aforesaid patent to Kimball No. 457,782. The strip of cardboard is introduced between the guides 70 and 71 from one end thereof and is advanced at proper intervals by means of feed rollers 94 and 95 between which it passes and to which an intermediate revolving motion is imparted as by means of a pawl 96 and ratchet 97, the latter being fixed to the shaft 98 of the roll 95 and the two rollers being geared together by suitable cog wheels 99 and 100. The pawl 96 is carried by an arm 101 which is hung on the shaft 98 of the lower feed roller and operated in any suitable manner as for example by the grooved cam 102 on the shaft 4.

The staple having been received between the anvil and the plunger 66 is in position to be bent by the plungers 72 and 73 which bend the points and loop downwardly over the edges of the anvil. The plunger 72 is slotted as indicated at 74 so as not to interfere with the retaining catch 63. The plungers 72 and 73 are connected to a collar 75 and operated by a lever 76 pivoted at 77 and controlled by the cam 78 on the rear cam shaft. The anvil is moved to and

from its operative position by a lever 79 pivoted at 80 and controlled by a cam 81 on the rear cam shaft against which cam the lever is held by a spring 82. The anvil is adapted to be retracted after the staple 70 has been bent around it by the plungers 72 and 73, and the plunger 66 then moves downwardly forcing the points of the staple through the blank 83 lying on the bed with its edge projecting over the recess 84 in the 75 bed. The staple is then in the position relative to the blank shown in Fig. 10. The plungers 66, 72 and 73 are mounted in a slot in the stand and are retained therein by the plate 51.

The loop of the staple is folded against the underside of the blank by a setting up tool comprising a slide 85 and a pivoted member 86. A fixed cam 87 co-operates with a cam surface 88 of the pivoted member 85 forcing the pivoted member upwardly at the end of its movement whereby the loop of the staple and the ends of the wire are bent closely against the underside of the card, the plunger 66 being held down against 90 the top of the blank during the operation of the setting up tool. A spring 89 bears down upon the pivoted member holding it in proper position. The setting up tool is slidably mounted in a guide 90 secured to 95 the bed and is operated by a lever 91 pivoted at 92 and controlled by a cam 93 on the rear cam shaft.

I have described but a single embodiment of my invention and it is to be understood that the form disclosed is illustrative merely and not restrictive.

Having fully described my invention, what I claim as new and desire to secure by Letters Patent is:—

1. Staple-forming mechanism comprising a die and a plunger co-operating to bend the wire to a U-shape and means to fold each end of said wire back upon itself thereby forming a staple presenting doubled wire 110 prongs.

2. A staple-forming mechanism comprising a die, a plunger movable relatively to said die to co-operate therewith to bend a wire to U-shape, folding mechanism adapted 115 to bend each side member of the U-shaped wire double and means to compress said doubled side members.

3. A staple-forming mechanism comprising a former presenting parallel flanges, a plunger, means for causing relative movement between the former and plunger whereby the plunger enters between the flanges of the former to bend a length of wire to U-shape, a folder and means for 125 causing relative movement between the former and folder whereby the free ends of said wire will be folded around said flanges thus forming a staple with doubled prongs.

4. A staple-forming mechanism comprising

ing a former presenting parallel flanges, a plunger, means for causing relative movement between the former and plunger whereby the plunger enters between the flanges of the former to bend a length of wire to U-shape, a folder, means for causing relative movement between the former and folder whereby the free ends of said wire will be folded around said flanges thus forming a staple with doubled prongs and means to compress the doubled prongs.

5. A staple-forming mechanism comprising a former presenting parallel flanges, a grooved plunger, means for causing relative movement between the former and plunger whereby the plunger enters between the flanges of the former to bend a length of wire to U-shape, a folder, means for causing relative movement between the former and folder whereby the free ends of said wire will be folded around said flanges thus forming a staple with doubled prongs and pivoted hammers operable to compress the doubled prongs into the groove of the plunger.

10. A staple-forming mechanism comprising a former presenting parallel flanges, a grooved plunger, means for causing relative movement between the former and plunger whereby the plunger enters between the flanges of the former to bend a length of wire to a U-shape with its sides lying between the plunger and the flanges of the former, a folder having grooved fingers and means to cause the grooved fingers to move along the outer faces of the flanges to bend the wire along said flanges.

15. A staple-forming mechanism comprising a support, a former presenting parallel flanges movable to and from operative positions, a grooved plunger mounted to slide on the support and between the flanges of the former to bend a wire to a U-shape, a folder mounted to slide on the support and having grooved fingers movable along the outer faces of the flanges to fold the ends against said flanges, hammers movable toward said plunger to compress the folded ends against the plunger after the former has been moved from operative position and means to move the former to and from operative position and to operate the plunger, folder and hammers.

20. A staple-forming mechanism comprising a former presenting parallel flanges, a plunger adapted to enter between said flanges and means to cause a relative coöperating movement thereof to bend the wire to a U-shape with the parallel parts lying along the inner faces of said flanges, and a folding mechanism comprising fingers, and means for operating said mechanism to cause said fingers to move along the outer faces of said flanges and fold the ends of the wire against said flanges.

9. A staple-forming mechanism comprising a former presenting parallel flanges, a plunger having a groove of a depth equal to twice the thickness of the wire of the staple and sliding between said flanges thus to bend the wire to a U-shape with its parallel parts lying in the groove of the plunger, a folding mechanism comprising fingers movable along the outer faces of said flanges to fold the ends of the wire against the outer faces of said flanges forming doubled prongs, means for retracting the former and means to compress the doubled prongs into the groove of the plunger.

10. A staple-forming mechanism comprising mechanism to deliver definite lengths of wire, a former presenting parallel flanges, a plunger of a size to fit closely between said flanges and having a groove of a depth equal to twice the thickness of the wire and movable between said flanges these to bend the wire to a U-shape, a folding mechanism comprising fingers movable along the outer faces of said flanges to fold the ends of the wire thereagainst, forming doubled prongs, means for retracting the former and means to compress the doubled prongs into the groove of the plunger.

11. A staple-forming mechanism comprising means for delivering definite lengths of wire, a die, a plunger having a groove of a depth equal to twice the thickness of the wire, means to cause relative movement between the die and plunger thus to bend the wire into the groove of the plunger and means to fold the ends of the wire double and press the folded ends into the groove of the plunger.

12. In a machine for making pin tickets the combination of means for delivering predetermined lengths of wire, mechanism for bending said lengths of wire to form staples having doubled wire prongs, card-feeding mechanism and staple-driving mechanism for affixing the staples to the cards.

13. In a machine for making pin tickets the combination of means for delivering predetermined lengths of wire, mechanism for bending said lengths of wire to form staples having doubled wire prongs, card feeding mechanism, staple driving mechanism for affixing the staples to the cards and means to carry the staples from the staple-forming position to the staple-driving position.

14. In a machine for making pin tickets the combination of mechanism to deliver definite lengths of wire, blank feeding mechanism, staple forming and transferring mechanism to bend each length of wire to form a staple and transfer such staples to a staple driving mechanism including means for bending the wire double at the points of each staple and staple driving mechanism for affixing the staples to the blanks.

15. In a machine for making pin tickets the combination of mechanism to deliver definite lengths of wire, staple-forming mechanism to bend the lengths of wire to 5 form staples including a device for doubling the ends of said wire so that the prongs of the finished staple will be formed of doubled wire folded at the points, blank feeding mechanism and staple driving mechanism 10 adapted to apply the staples to the blanks. 75
16. In a machine for making pin tickets the combination of mechanism to deliver definite lengths of wire, staple-forming mechanism to bend the lengths of wire to 15 form staples including a device for doubling the ends of said wire so that the prongs of the finished staple will be formed of doubled wire folded at the points, and staple driving mechanism adapted to apply the staples 20 to the blanks, the staple forming mechanism being arranged to transfer the staple from the staple-forming position to the staple driving position. 80
17. In a machine for making pin tickets 25 the combination of mechanism to deliver definite lengths of wire, wire folding mechanism including means to double the ends of the wire, means to operate the folding mechanism to cause it to bend the lengths of 30 wire to form staples having doubled prongs, blank-feeding mechanism, staple driving mechanism and means to operate the staple driving mechanism to affix the staples to the blanks. 85
18. In a machine for making pin tickets, in combination, feeding mechanism to feed 35 definite lengths of wire, mechanism to cut off such lengths of wire, staple-forming mechanism to bend each length of wire to 40 form a U-shaped staple including means for doubling the ends thereof, staple-driving mechanism to affix each U-shaped staple to a blank and means to carry automatically 45 the U-shaped staples from the staple-forming position to the staple-driving position. 100
19. In a machine for making pin tickets in combination mechanism to deliver definite 50 lengths of wire, a die having parallel flanges, a plunger movable between said parallel flanges, to bend the lengths of wire to U- 55 shape, a staple affixing mechanism, and operating means to cause the plunger to move between the parallel flanges to bend the wire to a U-shape and after a predetermined interval to give the plunger a further movement to deliver the staples to the staple affixing mechanism. 115
20. In a machine for making pin tickets in combination a former presenting parallel 60 flanges, a grooved plunger, means for causing relative movement between the parts whereby the plunger enters between the flanges of the former thereby bending the wire to a U-shape, mechanism for folding 65 the ends of the wire against the outer faces 120 of the flanges thus forming doubled prongs, means for retracting the former and the folding mechanism, hammers adapted to compress the doubled prongs against the plunger and arms carried by the hammers 70 normally spring pressed in advance of the hammers to engage the staple and hold it in position on the plunger before the folding mechanism is entirely retracted and until the hammers engage the staple. 75
21. In a machine for making pin tickets in combination a former presenting parallel flanges, a plunger, means for causing relative movement between the former and plunger whereby the plunger enters between the flanges of the former thereby bending a 80 length of wire to a U-shape, a folder to fold the ends around the parallel flanges to form doubled prongs, means to retract the former and folder, means to compress the prongs 85 against the plunger and means to temporarily hold the staple on the plunger prior to the operation of the compressing means. 90
22. In a machine for making pin tickets in combination a former presenting parallel 95 flanges, a plunger, means for causing relative movement between former and plunger whereby the plunger enters between the flanges of the former thereby bending a length of wire to a U-shape, a folder to fold 100 the ends around the parallel flanges to form doubled prongs, means to retract the former and folder means to compress the prongs against the plunger, and means carried by the hammers to engage the prongs and temporarily hold the staple in position on the plunger while the former is being retracted. 105
23. In a machine for making pin tickets in combination a former presenting parallel flanges, a grooved plunger means for causing relative movement between the parts whereby the plunger enters between the flanges of the former thereby bending the length of wire to a U-shape, mechanism for folding the ends of the wire against the 110 outer faces of the flanges, thus forming doubled prongs, means for retracting the former and the folding mechanism, hammers adapted to compress the prongs against the plunger, and means carried by the hammers to engage the staple and temporarily hold it in position on the plunger prior to the operation of the hammers. 115
24. In a machine for making pin tickets in combination a former presenting parallel 120 flanges, a grooved plunger, means for causing relative movement between the parts whereby the plunger enters between the flanges of the former, thereby bending the length of wire to a U-shape, mechanism for folding the ends of the wire against the outer faces of the flanges, thus forming doubled prongs, means for retracting the former and the folding mechanism, pivoted hammers arranged to move inwardly to press 130

the prongs into the groove of the plunger, arms pivoted to the hammers and normally spring pressed inwardly and operating means to hold the hammers retracted during the operation of the former, plunger and folding mechanism and to move the hammers inwardly sufficiently so that the pivoted arms may engage the staple before the folder is completely retracted and to move the hammers farther in to compress the prongs into the groove of the plunger.

25. In a machine for making pin tickets, mechanism to deliver definite lengths of wire a former presenting parallel flanges, a grooved plunger adapted to enter between the flanges of the former and bend the lengths of wire to a U-shape, folding mechanism comprising fingers movable along the outer faces of the flanges and adapted to fold the ends of the wire thereagainst, means to withdraw the former from the staple and hammers to compress the doubled prongs into the groove of the plunger the plunger being movable forwardly to deliver the staples and staple-driving mechanism adapted to receive the staples from the plunger

when in the forward position and to affix the staples to the blanks.

26. In a machine of the character described, staple forming mechanism comprising a die, a plunger to coöperate therewith, means to deliver definite lengths of wire, means to fold the ends of the wire double and means to operate said plunger to fold said wire to U-shape and to cause said plunger to deliver the staples in a definite position.

27. In a machine of the character described, in combination, means to deliver predetermined lengths of wire, means to bend the central portions of said lengths of wire to a U-shape and means to fold the ends of said lengths of wire double whereby staples having doubled wire prongs are formed.

In testimony whereof I have signed my name to this specification, in the presence of two subscribing witnesses.

HERMAN HEINE.

Witnesses:
